UNITED STATES PATENT OFFICE.

WILLARD F. RICHARDS, OF BUFFALO, NEW YORK, ASSIGNOR TO CHARLES M. GOULD, OF NEW YORK, N. Y.

ELECTRIC SWITCH.

SPECIFICATION forming part of Letters Patent No. 669,706, dated March 12, 1901.

Application filed November 20, 1899. Serial No. 737,570. (No model.)

To all whom it may concern:

Be it known that I, WILLARD F. RICHARDS, a citizen of the United States, residing at Buffalo, in the county of Erie and State of New 5 York, have invented new and useful Improvements in Electric Switches, of which the following is a specification.

The object of this invention is to construct the switch in such manner that the switch-lever is shifted from one set of contacts to the other and is brought into contact therewith by a rotary movement in a plane parallel with the face of the switchboard or base, thereby greatly simplifying the construction of the 15 switch and rendering the manipulation thereof easy and convenient.

In the accompanying drawings, Figure 1 is a face view of a switch embodying my improvements. Fig. 2 is a vertical section in line 2 2, Fig. 1. Fig. 3 is a section in a plane parallel with the face of the switchboard in line 3 3, Fig. 2. Fig. 4 is a horizontal section in line 4 4, Fig. 1. Fig. 5 is a fragmentary side elevation of the handle of the switch-lever, 25 showing the fixed adjusting-segment in section. Fig. 6 is a section through the handle of the switch-lever in line 6 6, Fig. 2. Fig. 7 is a perspective view of the locking-bolt and pointer of the switch-lever. Fig. 8 is a cross-30 section of one of the contacts and the blade of the switch-lever, showing the lever out of contact.

Like letters of reference refer to like parts in the several figures.

35 A represents the switchboard or base, which is preferably circular in outline and constructed of any suitable material—for instance, slate.

B represents a post, which is secured centrally to the face side of the base by screws b 40 or other means and on which the switch-lever turns.

C C' C² represent several contacts, which are secured to the face of the base around the central post B and equidistant therefrom. 45 The number and arrangement of these contacts may differ in different switches, as the special use for which the switch is designed may require.

The switch shown in the drawings is de-50 signed for use in an electric-lighting apparatus for railway-cars, in which a dynamo and two

storage batteries are employed. The switch is therefore provided with a comparatively long contact C for direct connection with the dynamo, two short contacts C' for connection 55 with opposite ends of the resistance which is interposed between the dynamo and the batteries, and two short contacts C² for connection with two parts of a lighting-circuit. The long contact C is arranged on one side of the 60 post B and the two short contacts C' are arranged near each other on the opposite side of the post. The short contacts C' are arranged diametrically opposite each other, one on each side, between the contacts C and C'. 65 Each contact is composed of a base-jaw c, a binding-post c', formed on the base-jaw, and a flexible jaw c², which is secured with its outer portion to the base-jaw and overhangs the latter with its free inner portion, the inner portions of both jaws being separated by a shoulder c³, formed on the outer portion of the base-jaw. The flexible jaw is secured to the base-jaw by soldering and also, as an additional safeguard, by pins c⁴. The base-jaw 70 is secured to the switch-base A by screws d or other means. Each contact is in this manner composed of two jaws which open inwardly or toward the central post.

E represents fuses which connect the binding-posts of the light-contacts C² with the binding-posts e, to which the lighting-circuits are connected.

F represents the blade of the switch-lever, F' the hub, and F² the handle thereof. The 85 hub F' is mounted on the central post B, and the blade F is secured to the end of the hub nearest the base by any suitable means—for instance, by soldering and pins. The blade F projects on diametrically opposite 90 sides from the hub F' and is of such length and arrangement with reference to the contacts that its end portions can be caused to enter between the jaws of either contact by turning the switch-lever on the post. In order to insure the tight fit of the blade between the jaws of the contacts, the blade is made slightly thicker than the space between the jaws, and in order to facilitate the entrance of the blade between the jaws the latter and the blade are beveled or rounded along their edges, as indicated in Fig. 8.

The handle F^2 of the switch-lever is attached to the hub by an insulated connection of any suitable construction, that shown in the drawings consisting of an arm g on the hub, insulating-washers g' , and fastening-screws g'' , which are surrounded by insulating-sleeves g^3 .

In the position of the blade F shown in Fig. 3 the blade connects the long contact C with both contacts C^2 . A short rotary movement of the switch-lever out of this position will break the contact with one of the contacts C^2 without breaking that with the long contact C . By turning the switch-lever to a position at right angles to that shown the two contacts C' are connected and the contact C is disconnected from the contact C^2 , as shown in Fig. 1. In order to hold the switch-lever in either of these positions, a segment H is secured to the base by posts h and bolts h' or other suitable means. This segment is provided in its outer face with V-shaped locking-notches h^2 . The switch-lever is held on the segment by a bolt I , which is pressed against the outer face of the segment by a spring i . The bolt and spring are seated in the handle F^2 of the switch-lever, and the bolt is provided with a double-beveled head by which it engages in the locking-notches, holding the lever yieldingly in position. By applying sufficient force to the handle the bolt is forced out of the notch, when the lever can be moved from one position to the other. The segment overlies that part of the handle which connects with the arm g of

the hub F' . The head of the bolt I is provided with an inwardly-tapering portion or pointer k , which bears against the front side of the segment, and the latter is provided with marks l , which are arranged in line with the notches h^2 , so that the position of the lever can be readily ascertained by means of the pointer and marks.

The switch-lever is shifted from one set of contacts to another by a simple turning movement in a plane parallel with the face of the base.

I claim as my invention—

The combination with the base, of a switch-blade pivoted on the base, contacts arranged on the base around the pivot of said blade, a segment secured to said base concentric with said pivot and provided with notches in its edge and with marks on its front side corresponding to the position of the contacts, a handle connected with the switch-blade and arranged in rear of the segment, and a spring-bolt arranged in the handle and provided at its end with a catch which is adapted to engage with the notches in the edge of the segment and with a pointer which traverses the marks on the front side of the segment, substantially as set forth.

Witness my hand this 13th day of November, 1899.

WILLARD F. RICHARDS.
